LUGGAGE LOCK

Wallace E. Atkinson, Petersburg, Va., assignor to Long Manufacturing Company, Inc., Petersburg, Va., a corporation of Virginia

Application December 20, 1957, Serial No. 704,127

3 Claims. (Cl. 70—75)

The present invention relates in general to luggage locks for suitcases and other receptacles where two adjacent separable parts of a receptacle are to be held together along their meeting edges, and more particularly, to locks of this type having a pivoted hasp and a manually operable push mechanism for releasing the lock.

An object of the present invention is the provision of a novel luggage lock of the pivoted hasp type which is of simple and novel construction permitting the lock to be economically manufactured with substantial savings in tools, dies, production and assembly costs.

Another object of the present invention is the provision of a novel hasp lock and keeper assembly wherein the keeper is of one piece construction and may be made in one operation on a progressive die.

Another object of the present invention is the provision of a novel luggage lock of the pivoted hasp type, wherein the hasp may be pivotally assembled to its mounting plate without the necessity of rolling the meeting edges of these elements to form hinge ears or employing a separate rivet for hingedly connecting them.

Another object of the present invention is the provision of a novel luggage lock of the pivoted hasp type wherein the lock works may be assembled with the hasp and the hasp pivotally assembled with its mounting plate, in one operation, and may be resiliently retained in this position by the biasing spring for the hasp.

Another object of the present invention is the provision of a novel luggage lock of the pivoted hasp type wherein the hasp body may be formed from sheet metal in a novel manner to improve the appearance thereof and to effect concealment of the lock works from observation from the front of the lock.

Other objects, advantages and capabilities of the present invention will become apparent from the following detail description taken in conjunction with the accompanying drawing illustrating one preferred embodiment of the invention.

In the drawing:

Figure 1 is a perspective view of a luggage lock embodying the present invention, illustrating the same in locked condition on a fragmentary suitcase section wherein the hasp is interlocked with the keeper;

Figure 2 is a perspective view of the luggage lock with the hasp in open or unlatched condition relative to the keeper;

Figure 3 is an exploded perspective view of the lock embodying the present invention; and

Figure 4 is a vertical longitudinal section view taken along the line 4—4 of Figure 1.

Referring to the drawing wherein like reference characters designate corresponding parts throughout the several figures, the luggage lock of the present invention, indicated generally by the reference character 10, comprises a hasp plate member 11 formed from sheet metal and having a front wall 12 apertured at 13 to receive rivets 14 for mounting the hasp plate member onto the

2

lid of a suitcase or the like, indicated at 15, top and bottom walls 16 and 17, and side walls 18. The front wall 12 is provided at its lower edge with an outwardly projecting cylindrical formation 19 extending the width of the hasp plate member 11. The side walls 18, and top and bottom walls 16, 17, are of sufficient width to project the front wall 12 a substantial distance from the surface of the suitcase lid 15 and form a hollow enclosure between these walls and the front wall 12.

10 The hasp body 20 is likewise formed from sheet metal and has a front wall 21, side walls 22, bottom wall 23, the side and bottom walls giving the hasp an appearance of substantial thickness and forming with the front wall 21 a rearwardly and upwardly opening casing for the 15 reception of the lock works generally indicated at 24. The front wall 21 of the hasp body 20 is provided with a key opening 25 surrounded by an embossed ring 26 to simulate the appearance of a rotary key cylinder. An integral tongue 27 projects upwardly from the upper edge 20 of the front wall 21 of the hasp body 20 and has a pair of oppositely projecting ears 28 extending from the lateral edges of the tongue 27 and a narrow transversely extending slot 29 located at the center of the tongue 27. An elongated box-like casing 30 formed from sheet metal 25 is disposed within the hollow of the hasp body 20 to house a push member 31 for rectilinear sliding movement within the casing 30. The casing 30 comprises a rear wall 32, side walls 33 and a top wall 34, the forward edge of the top wall 34 having an integral extension projecting upwardly therefrom in the plane of the free edges of the side walls 33 forming a mounting tongue 35 adapted to underlie the tongue 27 on the front wall 21 of the hasp body 20 and having a bendable lug 36 to be projected through the slot 29 and bent against the front 30 surface of the tongue 27. Mounting lugs 37 project from the lower edge of the rear wall 32 of the casing 30 through a slot in the bottom wall 23 of the hasp body 20. Thus, the casing 30 is assembled to the hasp body 20 by means of the lugs 36 and 37 projecting through the slot 40 in the tongue 27 and through a slot in the bottom wall 23. The push member 31 is essentially of channel-shaped construction and comprises a web 38 and a pair of forwardly projecting flanges 39 extending from the lateral edges of the web 38. The surfaces of the web 38 and flanges 39 conform closely to and are guided by the inner surfaces of the rear wall 32 and side walls 33 of the casing 30. An integral end wall 40 extends forwardly from the lower edge of the web 38 to the free edges of the flanges 39, and a wide finger piece 41 projects downwardly from the forward edge of the end wall 40 and through a slot 42 in the bottom wall 23 of the hasp body 20.

45 The web 38 of the push member 31 is provided with an intermediate opening 43 extending transversely entirely across the web 38, into which projects a latch tongue 44. The rear wall 32 of the casing 30 is also provided with an opening 45 which substantially registers with the opening 43 when the push member 31 is at its lowermost position.

50 The side walls 33 of the casing 30 are provided with laterally aligned openings 46 forming guide surfaces for a laterally reciprocable bolt 47 of conventional construction having the usual key follower surface 48, the bolt 47 being disposed transversely of the push member 31 and the flanges 39 being cut away to accommodate sliding movement of the push member 31 within the casing. A hairpin spring 48' has one leg bearing against the lower surface of the bolt 47 and another leg bearing against the shoulders 49 on the flanges 39 to continuously urge the push member 31 to its lowermost position within the casing 30.

The bottom wall 17 of the hasp plate member 11 is provided with an opening 50 therein for receiving the lapped tongue 27 of the hasp body 20 and the mounting tongue 35 of the casing 30 therethrough. The opening 50 has an enlarged portion 51 at the rearmost edge of the opening 50 of sufficient width to permit the ears 23 of the tongue 27 to pass therethrough, the forward portions of the opening 50 being constricted laterally to define an opening corresponding substantially to the width of the neck portion of the tongue 27. Accordingly, the widest portions of the tongues 27 and 35 may be projected through the enlarged portion 51 of the opening 50 until the top edges of the front wall 21 of the hasp body 20 abut the lower surface of the bottom wall 17 and the hasp body then projected forwardly so that the lateral bounding surfaces of the constricted portion of the opening 50 lie between the ears 23 of the tongue 27 and the upper edges of the front wall 21. The hasp body is maintained in this assembled relation with the hasp plate member 11 by means of the bent flat spring 52, by projecting the bent portion 53 of the spring 52 upwardly into the opening 50 between the rear surface of the tongue 35 and the rear edge of the opening 50. The rear edge of the opening 50 is relieved along the central portion thereof to provide a notch 54 extending the width of the spring 52, and the rear leg 55 of the spring 52 is provided with a curved end 56 adapted to seat on the edge of the notch 54. The front leg 57 of the spring 52 is bowed forwardly at the lower edge of the tongue 27 and the bent portion 53 bears against the front wall 12 when the spring is fully projected into the position illustrated in Figure 4 so that the free end of the leg 57 lies against the mounting tongue 35 of the casing 30 to urge the hasp body 20 outwardly. The spring 52 serves the dual function of retaining the tongue 27 of the hasp body 20 against the forward edge of the opening 50 in the hasp plate member 11 and to resiliently bias the hasp body 20 in a clockwise direction as viewed in Figure 4, to the open position illustrated in Figure 2. The interconnection between the hasp body 20 and hasp plate member 11 formed by the tongue 27 and opening 50 serve to pivot the hasp body for limited rotation about a transverse axis lying in the plane of the bottom wall 17 of the hasp plate member 11 and located at the front edge of the opening 50.

The body 20 is adapted to cooperate with a keeper member 58 formed of an integral piece of sheet metal and having a flat mounting plate portion 59 adapted to be secured to the lower section 60 of the suitcase and an outwardly projecting strike portion 61 defining a hollow for accommodating the latch tongue 44. The strike 61 is adapted to be projected through the opening 45 in the casing 30 when the hasp body 20 is pivoted downwardly from the open position of Figure 2 to the closed position of Figure 1 and the surfaces of the latch tongue 44 and of the strike 61 which engages the latch tongue 44 when the hasp body is shifted to closed position are shaped to cooperate to force the push member 31 upwardly against the bias of the spring 48' and permit the latch tongue 44 to pass inwardly of the lip 62 of the strike 61. The latch tongue 44 is then projected downwardly by the spring 48' to seat within the cavity formed by the strike 61 and retain the hasp body 20 in the locked position of Figure 4. The bolt 47 has an offset lug 47' struck therein which is positioned so as to be spaced laterally of the adjacent shoulder 49' at the top of the right flange 39 of the push member 31, as viewed in Figure 3, when in unlocked position, but which is disposed in the path of the shoulder 49' when the bolt is shifted laterally to the locked position to prevent upwardly displacement of the push member 31 from the latching position illustrated in Figure 4. When the bolt 47 is in unlatched position, the hasp body 20 may be released from the keeper 58 by pushing upwardly on the finger piece 41 to displace the push member 31 upwardly within the casing

30 and withdraw the latch tongue 44 from the strike 61. Upon withdrawal of the latch tongue 44 from the strike 61, the spring 52 will then shift the hasp body 20 outwardly about its pivotal connection with the hasp plate member 11 to the position illustrated in Figure 2.

5 While only one preferred embodiment of the invention has been particularly shown and described, it is apparent that other modifications may be made in the invention without departing from the spirit and scope thereof, and it is desired, therefore, that only such limitations shall be placed thereon as are imposed by the prior art and are set forth in the appended claims.

I claim:

1. A luggage lock comprising a hasp plate member 15 in the form of a rearwardly opening casing adapted to be affixed to a luggage lid, a keeper adapted to be affixed to a luggage base having a portion projecting outwardly therefrom, a hasp member having an upwardly projecting, substantially planar tongue integrally formed 20 at the upper end thereof provided with oppositely projecting ears at the lateral edges of said tongue and having a slotted lower end portion, lock works fixed to said hasp member and lying inwardly therefrom comprising a push member having an integral finger piece projecting 25 below the hasp member, a box-like casing housing the push member having surfaces guiding the push member for rectilinear reciprocal movement vertically of the hasp member, lug means projecting from the lower end of said box-like casing through the slot in the lower end 30 portion of said hasp member for securing said casing to said lower end portion, said box-like casing having an upwardly projecting tongue conforming at its upper end substantially to the shape of said hasp member tongue and disposed in underlying relation thereto, said hasp 35 plate member including a bottom wall having an elongated opening therein extending transversely of the hasp plate member and including a rearwardly disposed enlarged portion of sufficient size to permit the ears of said hasp member tongue and said casing tongue to pass 40 upwardly therethrough and a forwardly disposed constricted portion having lateral bounding surfaces spaced to extend beneath the ears of said tongues and form a pivotal support for the hasp member, spring means extending between the rear edge of said opening and the rear 45 surface of said casing tongue for resiliently positioning said tongues in intimate abutment with each other and in the constricted portion of said opening and continuously urging said hasp member outwardly about its pivotal support and away from said keeper, said push 50 member and said box-like casing having substantially aligned apertures for accommodating the projecting portion of said keeper therein and said push member having means associated with its aperture for selectively interlocking with said projecting portion of said keeper, and resilient means for continuously urging said push member downwardly to project the interlocking means 55 thereof into interlocking relation with the projecting portion of said keeper.

2. A luggage lock, comprising a hasp plate member 60 adapted to be affixed to a luggage lid and having a front wall and rearwardly projecting side, top and bottom walls, a keeper adapted to be affixed to the luggage base having an outwardly projecting strike, a hasp member having a 65 front wall and rearwardly projecting bottom and side walls forming a rearwardly opening housing, said hasp member bottom wall having a slot therein, a tongue formed integral with said hasp member front wall and projecting upwardly in the plane of said front wall, said tongue having oppositely projecting ears at the lateral edges thereof spaced from the upper edge of said hasp member front wall, lock works disposed rearwardly of said hasp member front wall and disposed within said hasp member housing comprising a vertically elongated 70 push member having an integral finger piece projecting 75

through said hasp member bottom wall to an exposed position therebelow, a box-like casing housing said push member having a rear wall spaced rearwardly from and paralleling said hasp member front wall and side walls projecting forwardly into abutment with said hasp member front wall, said rear and side walls of said casing being disposed in abutment with surfaces of said push member to guide the push member for rectilinear reciprocative movement vertically of said hasp member, lug means projecting from the lower end of said box-like casing into the slot in said hasp member bottom wall for removably anchoring the casing to said hasp member bottom wall and said box-like casing having an upwardly projecting tongue conforming at its upper end substantially to the shape of said hasp member tongue and disposed in underlying, aligned relation with the latter, the bottom wall of said hasp plate member having an elongated opening therein extending transversely of the hasp plate member and including a wider rear portion of sufficient width to permit the ears of said hasp member tongue and said casing tongue to pass upwardly therethrough and a narrower forward portion having bounding lateral surfaces spaced to extend beneath the ears of said hasp member tongue and form a pivotal support for the hasp member, a recurved flat spring having the curved portion thereof projected upwardly through said opening with the legs thereof compressed between the rear edge of said opening and said hasp member and casing tongues to resiliently position said tongues in the narrower portion of said opening, the curved portion of said spring projecting upwardly into said hasp plate member and bearing against the front wall thereof and said spring having a depending extension for continuously biasing said hasp member for rotation about its pivotal support with said hasp plate member in a direction away from said keeper, said push member and said casing having strike-accommodating apertures therein, said push member having a latch member projecting into its said aperture to interlock with the keeper strike when the strike projects into said strike-accommodating apertures, and spring means in said casing for resiliently urging said push member downwardly to project said latch member into interlocked relation with the keeper strike projecting through the strike-accommodating apertures.

3. A luggage lock, comprising a hasp plate member adapted to be affixed to a luggage lid and having a front wall and rearwardly projecting side, top and bottom walls, a keeper adapted to be affixed to the luggage base having an outwardly projecting strike, a hasp member having a front wall and rearwardly projecting bottom and side walls forming a rearwardly opening housing, a tongue formed integral with said hasp member front wall and projecting upwardly in the plane of said front wall, said tongue having oppositely projecting ears at the lateral edges thereof spaced from the upper edge of said hasp member front wall, lock works disposed rearwardly of

said hasp member front wall and disposed within said hasp member housing comprising a channel-shaped, vertically elongated, rectangular box-like casing housing said push member having a rear wall spaced rearwardly from and paralleling said hasp member front wall and side walls projecting forwardly into abutment with said hasp member front wall, said rear and side walls of said casing being disposed in abutment with the web and flanges of said push member to guide the push member for rectilinear reciprocative movement vertically of said hasp member, lugs projecting from the lower end of said box-like casing for anchoring the same to said hasp member bottom wall and said casing having an upwardly projecting tongue conforming at its upper end substantially to the shape of said hasp member tongue and anchored to said hasp member tongue in underlying relation thereto, the bottom wall of said hasp plate member having an elongated opening therein extending transversely of the hasp plate member and including a wider rear portion of sufficient width to permit the ears of said hasp member tongue and said casing tongue to pass upwardly therethrough and a narrower forward portion having bounding lateral surfaces spaced to extend beneath the ears of said hasp member tongue and form a pivotal support for the hasp member, a recurved flat spring having the curved portion thereof projected upwardly through said opening into abutment with the front wall of said hasp plate member with the legs thereof compressed between the rear edge of said opening and said hasp member tongue to resiliently position said tongue in the narrower portion of said opening, a leg of said spring having a downwardly projecting extension bearing against the front wall thereof for continuously biasing said hasp member for rotation about its pivotal support with said hasp plate member in a direction away from said keeper, said push member and said casing having strike-accommodating apertures therein, said push member having a latch member projecting into its said aperture to interlock with the keeper strike when the strike projects into said strike-accommodating apertures, spring means in said casing for resiliently urging said push member downwardly to project said latch member into interlocked relation with the keeper strike projecting through the strike-accommodating apertures, and a reciprocable, key-operable lock bolt supported in said casing having a portion selectively projectable into the path of said push member to bar upward movement of said push member from a keeper interlocking position thereof.
